WINDOW MEMBER EXTRUSION

Richard N. Anderson, Rome, Ga., assignor to V. E. Anderson Mfg. Co., Owensboro, Ky., a corporation of Kentucky

Filed Sept. 13, 1965, Ser. No. 86,979

Term of patent 14 years

(Cl. D13—6)

FIG. 1

FIG. 2

FIG. 3

FIG. 4

FIG. 7

FIG. 6

FIG. 5

FIGURE 1 is a perspective view of a window member extrusion showing my new design.

FIGURE 2 is a back view of the window member extrusion.

FIGURE 3 is a top view of the window member extrusion.

FIGURE 4 is a front view of the window member extrusion.

FIGURE 5 is a bottom view of the window member extrusion.

FIGURE 6 is a left end view of the window member extrusion.

FIGURE 7 is a right end view of the window member extrusion.

The dominant features of my design reside in the portions shown by means of full lines in the drawing.

I claim:

The ornamental design for a window member extrusion, substantially as shown and described.
